UNITED STATES PATENT OFFICE

152,216

DESIGN FOR A COMBINED BROOCH AND
LIPSTICK HOLDER

Joseph J. Quether, Trona, Calif.

Application November 10, 1947, Serial No. 142,411

Term of patent 7 years

(Cl. D86—10)

To all whom it may concern:

Be it known that I, Joseph J. Quether, a citizen of the United States, residing at Trona, in the county of San Bernardino and State of California, have invented a new, original, and ornamental Design for a Combined Brooch and Lipstick Holder, of which the following is a specification, reference being had to the accompanying drawing, forming part thereof.

The figure is a perspective view of a combined brooch and lipstick holder, showing my new design.

The back of the lipstick holder portion of the combined brooch and lipstick holder is substantially like the front shown.

I claim:

The ornamental design for a combined brooch and lipstick holder, as shown and described.

JOSEPH J. QUETHERA.
